United States Patent Office

Des. 209,384
Patented Nov. 28, 1967

209,384

DRESS

Lawrence J. Nachman, Greenville, S.C., assignor to Swirl, Inc., Easley, S.C., a corporation of South
Carolina

Filed Dec. 27, 1966, Ser. No. 5,197

Term of patent 14 years

(Cl. D2—80)

FIG. 1.

FIG. 2.

FIG. 1 is an enlarged elevational view of the neck ornament part of the dress shown in FIG. 2; and

FIG. 2 is a front elevational view of a dress showing my new design, the back being plain and conventionally styled.

I claim:

The ornamental design for a dress, as shown and described.
